TANK-CAR.

1,170,560.

Specification of Letters Patent.

Patented Feb. 8, 1916.

Application filed April 24, 1908. Serial No. 428,898.

To all whom it may concern:

Be it known that I, JOHN T. H. PAUL, citizen of the United States, residing at Chicago, in the county of Cook and State of Illinois, have invented a certain new and useful Improvement in Tank-Cars, of which the following is a full, clear, concise, and exact description, reference being had to the accompanying drawings, forming a part 10 of this specification.

My invention relates to tank cars, and has for its object the improvement in the construction thereof. As is well known to those skilled in this art, various ways have been 15 adopted for holding the tanks of tank cars against longitudinal displacement with respect to the under frames supporting the same. It has been common practice to pass rivets through the sheets of the tanks for 20 the purpose of holding the tanks in place. It is very apparent that this construction is faulty, for the rivets are subject to shearing strains and the holes in the tank sheets containing the shanks of the rivets are likely to 25 be enlarged and the tank sheets are likely to be warped and buckled where the rivets pass therethrough, whereby the life of the tanks is materially reduced. Moreover, the tanks are liable to severe injury and breakage, due 30 to the bumping the cars receive when the cars are in a train, also in switching, etc., for the main agency that prevents longitudinal movement between the tanks and the car bodies carrying the same are the anchoring 35 rivets.

I employ improved means for guarding the tanks of tank cars against the injurious effects of tank thrusts, which include cushions for absorbing such thrusts.

40 The preferred embodiment of my invention is exhibited in the accompanying drawings, in which—

Figure 1 is an elevation, partially in section, of one end of a car structure showing 45 the embodiment of my invention. Fig. 2 is a transverse sectional view through a portion of the structure where the tank is slidably mounted upon the car frame. Fig. 3 is an end view of the structure illustrated in 50 Fig. 2. Fig. 4 is a plan view of that portion of the frame upon which the tank is slidably mounted, a post carried by the tank being illustrated in section. Fig. 5 is a view from beneath looking upon that portion 55 of the tank that is provided with a post

that projects downward between the center sills.

Like parts are indicated by similar characters of reference throughout the different figures.

The tank 1 is suitably mounted upon an appropriate under frame comprising center sills 2 arranged and supported in any preferred manner, said tank being strapped in position in any suitable way by means of the 60 tank straps 3. One or more posts 4 project downwardly from the tank and are desirably fixed with respect thereto, there being two such posts for the tank in the preferred form of the invention. These posts 4 are 70 desirably each integrally formed with a downwardly extending flanges forming a resting plate 5 which is riveted to the bottom of the tank and having an upper surface conforming to the contour of the tank and 75 there engaging the tank. There are two such plates 5, one at each end of the car for each post, these plates being preferably disposed in close proximity to the truck bolsters in the form of the invention illustrated. Side bearings 6 are formed integrally with the elements 4 and 5 and project downwardly from the element 5, the lower surfaces of the side bearings 6 occupy 80 a horizontal plane or rather a plane parallel with the plane occupied by the rails of the track over which the car is passing. These lower surfaces of the side bearings 6 rest upon the outer end portions of suitable supports 7, the tank bands or straps 3 holding 85 the side bearings 6 down upon the supports 7, without, however, preventing the side bearings 6 from sliding upon the supports 7 when the tanks are subject to thrusts that are sufficiently severe to cause such sliding movement. These supports 7 may be 90 of any suitable shape, they desirably being in the form of cast plates that are bolted to the center sills of the under frame. Each plate 7 desirably extends across the space between 95 the center sills 8 and sufficiently beyond the center sills to afford ample bearing surface for the engaging side bearings 6. Each plate 7 has an aperture 9 provided therein that centrally receives a contiguous post 4, 100 the posts 4 being capable of longitudinal movement within the spaces 9, as will hereinafter appear. Spring-backed abutments or follower plates 10 carried by and movable longitudinally of the under frame or car 110

body extend into each space 9 and engage the post 4 entered into such recess. These abutments 10 are pressed into engagement with the posts 4 by means of powerful coil springs 11 carried by the under frame and acting longitudinally thereof, and whose ends opposite the abutments 10 engage suitable thrust plates 12 of a spring pocket hereinafter described and are secured in position with respect to the center sills. The powerful springs 11 acting through the abutments 10 and the posts 4, serve to maintain the tank in a given position, the springs upon one side of the posts or upon the other yielding when the under frames receive very severe thrusts, to prevent such thrusts from injuring the tank, the springs that have yielded expanding thereafter to re-locate the tank in its normal position. The movement which the tank need have is but slight, the tank bands or straps 3 permitting such movement, while the under flat surfaces of the side bearings 6, sliding upon the flat surfaces of the plate 7 afford suitable means for supporting the tank in position and at the same time, due to the friction between the bearings 6 and the plate 7 friction, retard the movement of the tank, at the same time permit the tank to move with respect to the under frame when such under frame receives excessive thrusts.

While I prefer to employ a plurality of posts 4 for each tank and a plurality of pairs of abutments for said posts, it is to be understood that I prefer this construction on account of the length of the tanks, though it is obvious that but one post with its spring-backed abutments will serve the purpose, particularly where short tanks are employed.

While I have herein shown and particularly described the preferred embodiment of my invention, I do not wish to be limited to the precise construction shown, as changes may readily be made without departing from the spirit of my invention.

It is to be noted that the plate 7 and the thrust plates 12, are preferably formed as a casting, as shown, and that such casting is of such area that its flanges overlie the center sills for a considerable part of their length, and are connected to such center sills by rivets A, which pass through the plate 7 and through the upper flanges B of the center sills, as best shown in Fig. 4. The thrust plates 12 are, as shown in said figure, cast and, with the bottom plate C, best shown in Fig. 1, said thrust plate and bottom plate form suitable spring pockets connected by means of the side plates D of such pockets shown in Fig. 2.

As the spring pockets are designed to receive the coil springs 11, it is desirable to provide means to prevent displacement of such springs during compression thereof, and this is provided for by extending the

plate 7 above the spring cavity, as shown in Fig. 1.

The truck E, illustrated in the dr. wings, may be of any suitable type but, for convenience, a so-called four-wheel truck is indicated and shown in longitudinal section, illustrating only a front wheel F and rear wheel G, with truck bolster H, center bearing I and truck side frame J. The center bearing I, as is usual, supports the superposed load, comprising the center sills, tank and tank anchor, which latter includes the members 4 to 12, inclusive, hereinbefore described.

It is obvious that the tank anchor may be positioned directly above the truck bolster, if desired, but another location is preferred and, as indicated, the tank anchor is positioned within the truck limits but nearer the middle of the car than it would be if placed immediately above such truck bolster.

By "within the limits of the truck" or within the truck limits is meant within the zone represented by lines extending vertically from the front of the front wheels F 90 and the rear of the rear wheels G.

Due to the side bearings 6 resting on the plate 7 intermediate the truck bolsters, the weight of the tank is applied to the center sills intermediate such truck bolsters, or supports for the center sills, whereby the weight thus supported is fulcrumed at the center bearings and the tendency of such application of the load is to lift the end portions K of the center sills and consequently the coupler L, which is usually carried thereby, and thus avoid the tendency, so common in tank cars, of the ends of the center sills to droop or fall below the required height prescribed by service requirements.

Tank anchors between center sills and tanks, near the middle of the tank, are not intended to support the tanks. On the contrary, such tank anchors cause the center sills to sag and tank bands are usually applied to pull the sills upwardly to the tank. In such constructions the weight of the tank and frequently of the sills is carried by body bolsters to which the sills are secured, such body bolsters resting on truck bolsters.

Where but one tank anchor of the type herein shown is employed, it is preferably positioned in vertical alignment with the body bolster, and where two are employed, as for example, one near each end of the tank, their positions should be substantially as indicated in Fig. 1, that is, within the truck limits but inside of the truck bolster, that is nearer the center of the car than is the position occupied by the truck bolster H.

It is obvious that the plate 7 may be braced at its outer ends and connected by such brace to the lower portion of the center sills in any approved manner, but such connection 130

forms no part of the present invention, and diagonal struts M are indicated for such purpose.

When a plurality of tank anchors is employed, as hereinbefore described, it is evident that the contact of the tank supporting and bearing members 6 with the plate 7 will be removed from the middle portion of the center sills and such members 6 will be supported by the center sills near their points of support—the center bearings—so that there will be but slight probability of the sills bending under stress due to the load. Additionally, more friction will follow movement of the tank on the under-frame or sills, due to the rubbing of the lower faces of the bearings 6 in contact with the plates 7, and friction means will be provided at each side of the middle of the tank 20 to retard movement of the tank longitudinally independently of the movement of the center sills.

Having thus described my invention, I claim as new and desire to secure by Letters Patent:—

1. The combination with a car body, of a tank, a post projecting downwardly from the tank and carried thereby, a bearing plate mounted upon the car body, bearing wings carried by the tank and slidably supported upon said bearing plate, said bearing plate having an aperture through which the post projects downwardly, a pair of abutments in association with said post movable longitudinally of the car body and between which said post downwardly projects, and springs carried by the car body and pressing said abutments against said post.

2. The combination with a car body, of a tank, a post projecting downwardly from the tank and carried thereby, a bearing plate mounted upon the car body, bearing wings carried by the tank and slidably supported upon said bearing plate, a pair of abutments in association with said post movable longitudinally of the car body and between which said post downwardly projects, and springs carried by the car body and pressing said abutments against said post.

3. The combination with a car body, of a tank, a post projecting downwardly from the tank and carried thereby, bearing wings carried by the tank and slidably supported upon the car body, a pair of abutments in association with said post movable longitudinally of the car body and between which said post downwardly projects, and springs carried by the car body and pressing said abutments against said post.

4. The combination with a car body, of a tank slidably supported thereupon, a post projecting downwardly from the tank and carried thereby, a pair of abutments in association with said post movable longitudinally of the car body and between which

said post downwardly projects, and springs carried by the car body and pressing said abutments against said post.

5. The combination with a car body, of a tank slidably supported thereupon, a post projecting downwardly from the tank and carried thereby, and a pair of spring-pressed abutments carried by the car body in association with said post movable longitudinally of the car body and between which said post downwardly projects.

6. The combination with a car body, of a tank, a post projecting downwardly from the tank and carried thereby, a bearing plate mounted upon the car body, upon which plate the tank is slidably supported, said bearing plate having an aperture through which the post projects downwardly, a pair of abutments in association with said post movable longitudinally of the car body and between which said post downwardly projects, and springs carried by the car body and pressing said abutments against said post.

7. The combination with a car body, of a tank, a post projecting downwardly from the tank and carried thereby, a bearing plate mounted upon the car body, upon which plate the tank is slidably supported, a pair of abutments in association with said post movable longitudinally of the car body and between which said post downwardly projects, and springs carried by the car body and pressing said abutments against said post.

8. The combination with a car body, of a tank, a plate upon which said tank is slidably supported, a post projecting through the plate and downwardly from the tank and carried by the tank, and a pair of spring-pressed abutments carried by the car body in association with said post movable longitudinally of the car body and between which said post downwardly projects.

9. The combination with one element in the form of a car body, of a second element in the form of a tank slidably supported upon the car body, a post located beneath the tank and projecting from one of said elements, and a pair of spring-pressed abutments carried by the other element and between which said post projects, thereby to relieve the tank of destructive action of violent thrusts.

10. In a tank car, an underframe, a tank supporting plate secured near one end of said underframe, said plate being provided with a central aperture extending longitudinally of said underframe, a spring pocket below said plate, tank cushioning means, and a tank provided with a depending member adapted to enter said aperture and contact with said cushioning means.

11. In a tank car, the combination comprising center sills, a sill cover plate having

- relatively central aperture; a tank saddle having integral side bearings, a post depending from said tank saddle within said aperture and cushioning means adapted to bear 5 on said post.
12. In a tank car the combination comprising center sills, a sill cover plate having relatively central aperture, an arcuate tank saddle, a post depending from said saddle 10 within said aperture and between said sills, and cushioning means adapted to bear on said post.
13. In a tank car, the combination comprising center sills, a cast member overlying 15 said sills, spring pockets secured between said sills, a tank, an arcuate tank saddle having an integral depending extension adapted to rest between said spring pockets, and springs held in said spring seats adapted to 20 bear on said extension.
14. A car structure including a tank; a supporting structure therefor upon which the tank may move longitudinally with respect to the supporting structure; a connection 25 rigidly secured to the bottom of the tank and moving upon the supporting structure; and means for preventing vertical movement between said connection and the tank supporting structure without preventing 30 said longitudinal movement of the tank.
15. A car structure including a tank; a supporting structure therefor upon which the tank may move longitudinally with respect to the supporting structure; a connection 35 rigidly secured to the bottom of the tank and sliding upon the supporting structure; and means for preventing vertical movement between said connection and the tank supporting structure without preventing 40 said longitudinal movement of the tank.
16. In a railway car, a truck, an underframe comprising a center sill, a car body adapted to have slight longitudinal movement independently of said underframe, a suitable longitudinally disposed coil spring, 45 a follower plate, and a member projecting down from said car body within the limits of said truck and opposing said follower plate.
17. In a railway car, an underframe comprising a center sill and a body bolster, a truck comprising front and rear wheels and axles, a car body adapted to have slight longitudinal movement independently of said 50 underframe, a pocket for a cushioning device between said axles and car body, a longitudinally disposed coil spring and a follower plate in said pocket, and a member secured to and depending from said car body 55 adapted to contact with said follower.
18. In a railway car, a center sill, a car body mounted to have slight movement independently and longitudinally of said center sill, a pocket for a cushioning device formed independently of and supported 65 within the vertical limits of said center sill, said pocket comprising a casting having end walls, a coil spring in said pocket, a follower adapted to abut said spring, and a member depending from said car body adapted to 70 contact with said follower.
19. In a tank car, a truck, a center sill, a tank, a body bolster, a cast metal spring pocket having end walls, longitudinally disposed resilient means in said spring pocket, 75 a follower in alignment with said resilient means, and a member depending from the tank into said spring pocket, said last mentioned member having flanges adapted to be secured to said tank.
20. In a tank car, spaced center sills, a tank, a casting secured to both center sills, a casting secured to said tank and depending therefrom into frictional contact with said first mentioned casting and adapted to retard movement of the tank relatively to said sills, and a plurality of springs co-operating therewith.
21. In a tank car, spaced center sills, a tank, a casting secured to both center sills, 85 a flanged casting secured to said tank and depending therefrom into frictional contact with said first mentioned casting and adapted to retard movement of the tank relatively to said sills, and a plurality of springs co-operating therewith.
22. In a tank car, spaced center sills, a tank, a casting secured to both center sills, a casting secured to said tank and depending therefrom into frictional contact with said first mentioned casting and adapted to retard movement of the tank relatively to said sills, and a plurality of springs, one on each side of said casting, secured to the tank 90 adapted to co-operate with said friction elements.
23. In a tank car, center sills spaced apart, a tank, a friction element connected to each of said sills, a flanged casting secured to said tank and depending into contact with 95 said friction element, and a plurality of coil springs spaced apart and mounted in position to co-operate with said friction elements to permit limited movement of the tank independently of said sills.
- In witness whereof, I hereunto subscribe my name this 18th day of April A. D. 1908.
